5 Claims. (Cl. 137—103)

This invention is for improvements in or relating to devices for regulating the flow of refrigerant in refrigerating plant. The invention is particularly concerned with regulating devices 5 of the type which embody float-operated valves interposed between the condenser and the evaporator and which have the float-chamber under the condenser pressure. These regulating devices are intended to pass liquid from the condenser 10 to the evaporator, and it is desirable that as little gas or vapour should be allowed to pass as possible.

In regulating devices of this type as heretofore proposed a difficulty is sometimes experienced 15 in getting the liquid to flow from the condenser into the float-chamber. This difficulty is especially liable to occur if the float-chamber is located at a level above the condenser. Another 20 difficulty which is sometimes experienced is that the float-chamber becomes "gas-bound". That is to say, the float becomes locked in a position in which it maintains the valve closed. In order to overcome this difficulty a vent pipe or leak 25 passage has been proposed to allow gas or vapour to escape from the upper part of the float-chamber to the evaporator. Owing, however, to the great difference between the pressure in the condenser and that in the evaporator, a relatively 30 large amount of gas or vapour will escape even when the vent pipe has the smallest bore practicable.

It is an object of the present invention to provide a construction of regulating device which shall not be subject to these objections.

According to the present invention in an evaporative refrigerating apparatus there is provided between the condenser and the evaporator 35 an automatic regulating device comprising a float-chamber, a bell-float therein, means for introducing fluid from the condenser beneath the bell-float, a leak in the upper part of the float, a discharge port in the float chamber connected to the evaporator and so disposed as to retain at 40 sufficient working fluid therein to seal the bell at all times, a discharge valve for the port and operative connections from the float to the discharge valve such that the valve is closed when the float rises.

It will be appreciated that the leak will enable 45 the gas or vapour pressure inside and above the bell to equalize themselves thus permitting the bell to fall under its own weight and open the valve. There will therefore be no likelihood of the float becoming "gas-bound". Upon the 50 valve opening the gas in the float-chamber will

escape to the evaporator until the float-chamber pressure falls sufficiently to admit liquid from the condenser and this liquid will flow through the regulating device until the liquid in the condenser is exhausted, whereupon the flow of gas 5 from the condenser will fill the bell with gas and cause the valve to close by the rising of the bell. Therefore the pressure in the condenser will always be able to cause discharge into the float-chamber. 10

Preferably, the discharge port is situated in a well separated from the float-chamber by a weir. The weir should be preferably not higher than the top of the float when the valve is closed—preferably slightly below the top of the float in 15 this position.

Preferably, the float encloses a substantially larger horizontal sectional area than the space around it in the float-chamber and it is so positioned that when the valve is closed the float 20 is not entirely submerged. Consequently, when liquid flows into the float from the float-chamber when the valve is closed the level in the float-chamber falls rapidly for even a small flow of liquid into the float and the opening of the valve 25 occurs more promptly. In other words, the device is more sensitive and less gas needs to flow from the condenser for the purpose of operating the float.

The following is a description by way of example of one construction in accordance with the invention with reference to the accompanying drawing, in which— 30

Figure 1 is a vertical section of a regulating device in accordance with the invention, and 35

Figure 2 is a plan of the same with the cover removed.

In the drawing, 11 is a casing of a float-chamber 12, which casing is designed to withstand an internal pressure equal to that of the condenser 40 of the refrigerating apparatus in which the regulating device is to be employed. The casing 11 is provided with a removable cover 13 held by set screws 14 and it has an inlet 15 and an outlet 16, the inlet 15 being intended to be connected 45 to the outlet for condensed liquid of the condenser, while the outlet 16 is to be connected to the evaporator.

The outlet 16 is located at the bottom of a well 17 on the side of the casing 11 and between the well 17 and the outlet passage 16 there is an outlet port 18 in a valve seating 19. The well 17 is separated from the float chamber 12 by a weir 20. On the edge of the weir there is supported a bearing 21 for the pivot 22 of a float- 50 55

lever 23. The float-lever is pivoted at 24 to the stem of a conical valve 25 which works on the seating 19 and serves, when closed, to seal the outlet port 18. At the other end of the float-lever 23 there is hung by a pivot pin 26 a bell-float 27. The bell-float is made of a diameter very little smaller than the dimensions of the inside of the casing 11 of the float-chamber and it is open at the bottom end so that its open underside overlies the end of a pipe 28 screwed into the inlet 15. In its upper wall the bell-float 27 is provided with a small leak aperture 29. The weight of the float must be so proportioned that when the interior of the bell is filled with liquid, it will be heavy enough to sink and pull the valve off its seat against the condenser pressure, and it must at the same time be light enough to float when a sufficient quantity of liquid from the interior is displaced by gas.

In the operation of this regulator, assuming the parts to be in the position shown in the drawing with the bell-float 27 sunk to its lowermost position and the valve 25 open, liquid is forced from the condenser through the inlet 15 into the float-chamber 12 and the entry of this liquid causes an overflow over the weir 20 into the well 17 and out through the valve and port 18 to the evaporator. As soon as the liquid available in the condenser has all flowed into the float-chamber a small amount of gas comes through the inlet 15 and entering below the bell 27 it displaces the liquid therein, causing the displaced liquid also to overflow the weir and pass to the evaporator. As soon as the amount of gas in the bell is sufficient to give it buoyancy the bell is caused to rise and to close the valve 25. Gas continues to flow into the float-chamber for a short time until the pressure in the regulating device rises to the pressure in the condenser. Flow then ceases and liquid accumulates in the condenser while the gas beneath the bell gradually leaks out through the leak hole 28. As a result the buoyancy of the bell decreases and the bell begins to sink. The leaking of the gas out of the bell-float allows some of the liquid in the float-chamber 12 to pass back into the bell-float and as the cross-sectional area enclosed by the bell is much greater than the surrounding horizontal area in the float-chamber, the corresponding fall of liquid level in the float-chamber will be rapid. A small transfer of gas from beneath the bell to the space above it will therefore suffice to cause the bell to sink again, partly by the loss of buoyancy and partly by the fall of liquid level in the float-chamber. The valve 25 will therefore very soon open again, whereupon any small quantity of liquid in the well 17 is first discharged to the evaporator, followed by a small quantity of gas from the upper part of the float-chamber, so that the pressure, which had been equal to the condenser pressure, now falls sufficiently to permit the entry of further condensed liquid from the condenser.

The cycle of operations is then repeated. Owing to the arrangements for the prompt opening of the valve with a slight leakage through the leak hole 28 the apparatus is highly sensitive and works with only a very small amount of gas 5 passing to the evaporator, much smaller than the amount of gas which would pass by a direct leak from the space in the float-chamber to the evaporator in the known apparatus as hereinbefore referred to.

I claim:—

1. In an evaporative refrigerating apparatus, the provision between the condenser and the evaporator of an automatic regulating device comprising a float chamber, a bell-float therein, means 15 for introducing fluid from the condenser beneath the bell-float, a well adjacent the float chamber and connected thereto, a discharge port in the well connected to the evaporator, the well being so disposed as to retain sufficient working fluid 20 in the float chamber to seal the open end of the bell-float at all times, a discharge valve for the port, and operative connections from the bell-float to the discharge valve such that the valve is closed when the bell-float rises. 25

2. In an evaporative refrigerating apparatus an automatic regulating device as claimed in claim 1 wherein the said well is separated from the float-chamber by a weir and said discharge port is below the weir. 30

3. In an evaporative refrigerating apparatus an automatic device as claimed in claim 1 wherein the float is so positioned in the float-chamber that when the valve closes the level of the liquid in the float-chamber is not above the upper wall of the float substantially as and for the purpose described. 35

4. In an evaporative refrigerating apparatus an automatic device as claimed in claim 1 wherein the float is so positioned in the float-chamber that when the valve closes the level of the liquid in the float-chamber is not above the upper wall of the float and wherein the float encloses a substantially larger horizontal sectional area than the space around it in the float-chamber, for the purpose described. 40 45

5. An automatic regulating device for an evaporative refrigerating apparatus comprising in combination a float-chamber having a discharge port located at a level above the bottom of the 50 chamber, a discharge valve for the discharge port, a bell-float in the chamber operatively connected to the discharge valve whereby the valve is directly moved by the bell so as to open the same when the float sinks, a leak in the upper part of the float, an inlet for fluid from the condenser of the refrigerating apparatus beneath the bell-float and a weir between the bell-float and the discharge valve of such height as to permit the float to be substantially completely immersed in the liquid 55 in the float-chamber when the valve is opened. 60
